UNITED STATES PATENT OFFICE.

MABEL KLEIN, OF ST. LOUIS, MISSOURI.

DESIGN FOR A RECEPTACLE INCLOSURE.

Application filed March 14, 1925. Serial No. 12,718. Term of patent 8½ years.

To all whom it may concern:

Be it known that I, MABEL KLEIN, a citizen of the United States, residing at the city of St. Louis and State of Missouri, have invented a new, original, and ornamental Design for a Receptacle Inclosure, of which the following is a specification, reference being had to the accompanying drawing, forming part thereof.

In the drawing Fig. 1 is a front elevation showing my new design for a receptacle inclosure.

Fig. 2 is a side elevation.

I claim:

The ornamental design for a receptacle inclosure, as shown.

MABEL KLEIN.
